[57] CLAIM

I claim the ornamental design for a compressible door track magnet module, as shown and described.

DESCRIPTION

FIG. 1 is a top, front isometric view of a compressible door track magnet module according to my new design;

FIG. 2 is a bottom, front isometric view thereof;

FIG. 3 is an elevational view of either the front or back side thereof;

FIG. 4 is an elevational view of either the right or left side thereof;

FIG. 5 is a top plan view thereof; and,

FIG. 6 is a bottom plan view thereof.
